ANTISEPTIC SOAP COMPOSITION

Roland S. Shumard, Brentwood, Mo., assignor to Monsanto Chemical Company, St. Louis, Mo., a corporation of Delaware

No Drawing. Application April 21, 1952,
Serial No. 283,491

7 Claims. (Cl. 252—107)

This invention relates to new and useful detergent compositions. More particularly it relates to detergent compositions containing a beta-aryloyl acrylic acid or a salt or an ester thereof exhibiting antiseptic properties.

In accordance with this invention it has been found that compounds of the general formula

where R is an aromatic hydrocarbon radical such as phenyl, tolyl, ethylphenyl, n-propylphenyl, cumyl, n-butylphenyl, tert. butylphenyl, n-amylphenyl, sec. amylphenyl, (2-ethylhexyl)phenyl, xylyl, cymyl, trimethylphenyl, triethylphenyl, cyclohexylphenyl, benzylphenyl, phenethylphenyl, biphenyl, naphthyl, etc. and where A is hydrogen or an alkali metal or an aliphatic radical when admixed with a detergent composition in minor proportions forms a detergent product exhibiting excellent antiseptic properties.

For purposes of this application the beta-aryloyl acrylic acids, salts and esters thereof are termed antiseptic agents hereinafter.

The antiseptic agents of this invention are readily incorporated in detergent compositions whether the latter be solid or liquid. The new antiseptic agents are non-volatile and remain permanently in the detergent composition. They do not affect the lathering, cleansing or physical properties of the detergent nor do they impart any unpleasant odors nor discolor the finished detergent composition.

As exemplary of this invention, detergent containing compositions are prepared by intimately mixing the ingredients listed below to form a composite containing 2% by weight "active ingredient."

Composition	A (parts by weight)	B (parts by weight)
"Ivory" brand neutral white high grade toilet soap (a mixture of 80% sodium soap and 20% potassium soap produced from a 70% tallow and 30% coconut oil glyceride blend in accordance with U. S. 2,295,594)	98	98
Beta-benzoyl acrylic acid	2	2
Methyl beta-benzoyl acrylate	—	—

Aliquots of each of the above described compositions containing 2% by weight "active ingredient" are added to a nutrient agar medium so as to give in each instance a concentration of 10 p. p. m. (1:100,000) of "active ingredient." The agar in each case is then poured into a Petri dish, allowed to harden and then is streaked with a 24 hour old culture of *Salmonella typhosa* of standard resistance. The incubation in each case is made at 37° C. for 72 hours and the degree of bacterial growth is noted below:

Table I

Composition	A	B
Growth	no growth	no growth

2

Composition A upon further dilution with nutrient agar so as to give a composition having a concentration of 1 p. p. m. (1:1,000,000) of active ingredient upon being streaked with a 24 hour old culture of *Salmonella typhosa* of standard resistance after incubation at 37° C. for 72 hours exhibited no signs of bacterial growth.

Replacing either of the respective antiseptic agents of Compositions A and B above with any one of the following:

- 10 Sodium beta-benzoyl acrylate
  - Potassium beta-benzoyl acrylate
  - Ethyl beta-benzoyl acrylate
  - Isopropyl beta-benzoyl acrylate
  - 15 n-Butyl beta-benzoyl acrylate
  - Beta-(m-methyl-benzoyl) acrylic acid
  - Beta-(o-ethyl-benzoyl) acrylic acid
  - Beta-(p-n-hexyl-benzoyl) acrylic acid
  - Sodium beta-(p-n-hexyl-benzoyl) acrylate
  - 20 Beta-(p-phenyl-benzoyl) acrylic acid
  - Potassium beta-(p-phenyl-benzoyl) acrylate
- and evaluating in same manner, satisfactory control of *Salmonella typhosa* is obtained.

As further exemplary of this invention, detergent compositions are prepared by intimately mixing the ingredients listed below to form a composite containing 2% by weight "active ingredient."

Composition	C (parts by weight)	D (parts by weight)
"Ivory" brand neutral white high grade toilet soap (a mixture of 80% sodium soap and 20% potassium soap produced from a 70% tallow and 30% coconut oil glyceride blend in accordance with U. S. 2,295,594)	98	98
Methyl beta-benzoyl acrylate	2	2
Beta-(p-phenyl-benzoyl) acrylic acid	—	—

40 Aliquots of each of the above described compositions containing 2% by weight "active ingredient" are added to a nutrient agar medium so as to give in each instance a concentration of 10 p. p. m. (1:100,000) of "active ingredient." The agar in each case is then poured into a Petri dish, allowed to harden and then is streaked with a 24 hour old culture of *Micrococcus pyogenes* var. *aureus* of standard resistance. The incubation in each case is made at 37° C. for 72 hours and the degree of bacterial growth noted below:

Table II

Composition	C	D
Growth	no growth	no growth

55 Replacing the respective antiseptic agents of Compositions C and D above with any one of the following:

- 60 Ethyl beta-benzoyl acrylate
- Isopropyl beta-benzoyl acrylate
- Sec. amyl beta-benzoyl acrylate
- n-Octyl beta-benzoyl acrylate
- Methyl beta-(p-methyl-benzoyl) acrylate
- 65 Methyl beta-(p-isopropyl-benzoyl) acrylate
- Ethyl beta-(p-phenyl-benzoyl) acrylate
- Sodium beta-(p-phenyl-benzoyl) acrylate
- Potassium beta-(p-phenyl-benzoyl) acrylate
- Methyl beta-(p-phenyl-benzoyl) acrylate
- Beta-naphthyl acrylic acid

70 and evaluating in the same manner satisfactory control of *Micrococcus pyogenes* var. *aureus* is obtained. In the

control of *Micrococcus pyogenes* var. *aureus* compounds of the formula

where A is a short chain alkyl radical and where R is a benzenoid hydrocarbon radical are particularly effective.

Relatively small amounts of the new antiseptic agents in a detergent composition have been found to yield efficient antiseptic detergent compositions. Amounts as low as 0.5 to 1% by weight based upon the weight of the detergent have proved satisfactory in some instances. However, it is preferred to employ amounts in the order of 1-3% by weight. While larger amounts may be employed, as for example up to 10% by weight based upon the weight of the detergent, the upper limit will be determined by practical consideration. Other antiseptic agents may be incorporated as well as emollients, water softeners and the well-known "vehicles" of the soap trade. Various colors, antioxidants, perfumes and the like may be included where desirable.

The term "detergent" includes soap and the synthetic detergents such as the Turkey red oils, the highly sulfonated fatty acids and the sulfated fatty alcohols. The term "detergent" includes also mixtures of synthetic detergents and soap. The term "soap" or "detergent soap" as used herein is employed in its popular or ordinary meaning, that is, those cleansing compositions, namely the well-known washing toilet and liquid soaps prepared from an alkali metal compound such as sodium or potassium hydroxide and a fat or fatty acid.

The antiseptic agents of this invention may be added to the detergent compositions during the crutting or melting or similar operation. The new antiseptic agents may be first dissolved in a suitable solvent and then incorporated in the detergent if so desired. In general, any method which results in the new antiseptic agent of this invention being uniformly incorporated in the final composition is satisfactory.

What is claimed is:

1. An antiseptic detergent composition comprising a detergent soap and 0.5 to 10% by weight based upon the detergent soap of a compound of the formula

where R is an aromatic hydrocarbon radical containing not more than 14 carbon atoms and where A is selected from the group consisting of hydrogen, sodium, potassium and alkyl radicals containing not more than 8 carbon atoms.

10 2. An antiseptic detergent composition comprising a detergent soap and 1-3% by weight based upon the detergent soap of a compound of the formula

where R is a benzenoid hydrocarbon radical and where A is a short chain alkyl radical.

15 3. An antiseptic detergent soap composition comprising a detergent soap and 1-3% by weight based upon the detergent soap of beta-benzoyl acrylic acid.

4. An antiseptic detergent soap composition comprising a detergent soap and 1-3% by weight based upon the detergent soap of sodium beta-benzoyl acrylate.

20 5. An antiseptic detergent soap composition comprising a detergent soap and 1-3% by weight based upon the detergent soap of methyl beta-benzoyl acrylate.

30 6. An antiseptic detergent soap composition comprising a detergent soap and 1-3% by weight based upon the detergent soap of ethyl beta-benzoyl acrylate.

7. An antiseptic detergent soap composition comprising a detergent soap and 1-3% by weight based upon the detergent soap of beta-(p-phenyl-benzoyl) acrylic acid.
